UNITED STATES PATENT OFFICE

EDWARD A. QUINN, OF FRESNO, CALIFORNIA.

REISSUED

COMBINED OIL AND GAS FURNACE.

Application filed November 30, 1921. Serial No. 516,985.

To all whom it may concern:

Be it known that I, EDWARD A. QUINN, a citizen of the United States, and resident of Fresno, in the county of Fresno and the 5 State of California, have invented a new and useful Improvement in Combined Oil and Gas Furnaces, of which the following is a specification.

My invention relates to an improved type 10 of furnace wherein either oil or gas can be used for fuel. The object I have accomplished is the construction of a combination furnace in which manufactured or natural gas can be used economically as fuel, and 15 if it is desired oil can be substituted, and heat developed from one burner will not overheat or melt the other burner.

I attain these objects by the device hereinafter described and illustrated in the accompanying drawings, in which Figure 1 is a plan view of the furnace showing the two burners within the combustion chamber. Figure 2 is an elevation of the device, partly 25 in section along broken line *a—a* in Figure 1, showing the location of tiles in which the gas is discharged. This view also shows location of oil burner in relation to the gas burners. Figure 3 is a front elevation along sectional line *b—b* in Figure 1. Figure 4 is a sectional elevation of two gas 30 burners. Figure 5 is a view of a tile. Figure 6 is a cross sectional view of the tile along the line *c—c* in Figure 5. Similar reference characters refer to similar 35 parts throughout the several views.

Branch header 1 is connected to source of fuel supply 2, and is supported by rods 3, the ends of which are supported by the furnace walls. Nipples 4 are connected to 40 branch header 1 as shown more definitely in Figure 4, their ends being closed by caps 5, in order to force the gas to flow through small hole or opening 6 in nipple 4. A tile 7 is set over each nipple 4, a longitudinal 45 slot 8 being provided in the bottom of tiles 7 for the purpose of easily assembling the nipples and the tiles. Tiles 7 are held in position by brick floor 9, said floor resting on supporting rods 3^a. Floor 9 is constructed 50 to the tops of the tiling. On the top of floor 9 is a course of fire bricks 10 arranged to leave apertures above the openings in the tiling. It is here noted that the floor 9 is on an incline which rises as it recedes 55 from the oil burner 14. When it is neces-

sary to use oil burner 14 the flame and heat are reflected upward by said floor.

I have placed a course of soap bricks 11 on the top of the fire bricks 10, and over the openings in the tiles, thus forming an open 60 space 12 shown in Figure 3. Soap bricks 11 form a baffle for the flame and gas coming out of the tiling. One object being accomplished thereby is the breaking up of the gas and thus aiding combustion. Openings 65 in the floor except the openings 12 referred to are filled in with asbestos and clay.

The tile 7 has a plurality of holes 13 in a circumferential line on the same plane as the center line of the nipple 4, as shown in 70 Figure 5. The function of holes 13 is to admit air to aid combustion. The shutters 18 are hinged to rod or pipe 3, and are adjustable by a chain or rod 18^a.

The oil burner 14 is placed in a compartment or alcove 15 at the back of the furnace, and so placed as to direct the flame over the soap brick baffles 11, as the flame and heat natural reflect upwardly, the object 75 of this construction being to carry the flame 80 beyond the alcove. The fuel supply pipe 16 to the oil burner is supported by rods 17, and is connected with a source of oil supply 26. 26^a is a valve for regulating the supply 85 of oil admitted to the burner. 2^b is a valve 85 for regulating the supply of gas admitted to the furnace. The combustion chamber is constructed of concrete and fire brick. The rods or pipes 3 and 17 are supported by fire 90 brick walls.

I claim as new and ask for Letters Patent:

1. The combination within a combustion chamber of an oil burner adapted to direct a flame in an approximately horizontal plane a spaced distance therefrom, and a 95 plurality of gas burners, each of the gas burners being housed within a tiling arranged so the tops thereof are on an incline which rises as it recedes from the oil burner, the tops of the tiling being covered with 100 refractory material except outlet openings for the flame generated within said tiling, substantially as described.

2. The combination within a combustion chamber of an oil burner adapted to direct 105 a flame in an approximately horizontal plane a spaced distance therefrom, and a plurality of gas burners, each of the gas burners being housed within a tiling arranged so the tops thereof are on a line uniformly 110

rising from said horizontal plane as they recede from the oil burner, the tops of the tiling being covered with refractory material except outlet openings for the flame generated within said tiling, the combustion chamber being filled with noncombustible material to the approximate tops of the tiling, leads for supplying air to the interior of the tiling, substantially as described.

10 3. In combination with a combustion chamber, a gas burner within said chamber consisting of upright tubes of refractory material, means for discharging a jet of gas within each of said tubes, a plurality

of holes through the walls of the tubes adjacent to the position where the gas is discharged, said tubes being partially covered at the top with refractory material, the tubes being arranged so that the level of the tops of the tubes to the rear of the furnace are lower than those near the front of the combustion chamber, and an oil burner within the combustion chamber at the rear end thereof adapted to throw a flame over the top of the tubes, substantially as described.

EDWARD A. QUINN.
